AMPLIFYING CIRCUIT FOR MICRO-WAVES, ESPECIALLY MILLIMETER WAVES

Georges Robert Pierre Marié, Paris, France

Application December 14, 1954, Serial No. 475,078

Claims priority, application France December 28, 1953

4 Claims. (Cl. 179—171)

The present invention relates to amplifying circuits for amplifying micro-wave signals, and more particularly to amplifiers for amplifying signals whose wave lengths are in the order of millimeters.

Briefly, a circuit of the invention consists essentially of a rod of ferrite, or of a dielectric material having a very high magnetic permeability. A D. C. magnetic field is directed along the axis of the rod and the rod is situated along the axis of a cavity, cylindrical in shape, into which electromagnetic energy is injected in the form of a TM_{11} wave polarized circularly and having a frequency very definitely lower than that of the wave to be amplified. For instance if it is desired to amplify a wave having a frequency of 50,000 mc./s. a frequency of the order of 5,000 mc./s. will be taken as a frequency for the circularly polarized wave.

The ultra high frequency wave to be amplified is propagated before and after amplification, in circular coaxial guides, coaxial with the ferrite rod, in the shape of a TE_{01} wave. The energy exchange is effected through the medium of the motions in the direction of the spin of electrons. The circularly polarized wave with a relatively low frequency imparts energy to the electrons located in the ferrite rod and the direction of their spin has a precession motion accompanied by a nutation motion imparted thereto. The ultra high frequency wave is amplified by deriving energy from the nutation motion of the electrons. In the present specification and for greater convenience in expression, the wave having a relatively low frequency shall be called the "supply wave."

The invention will be better understood from the detailed description which will next be given in connection with the appended drawings, wherein:

Figure 1 represents a perspective view of an amplifier circuit in accordance with the invention.

Figure 2 is a geometrical diagram utilized in explaining the operation of the circuit in Figure 1.

The amplifying circuit comprises a cylindrical cavity 2 along the axis of which a ferrite rod 3 is located. The cavity 2 is coupled with an input circular guide 4 through which the energy to be amplified arrives and with an output circular guide 5 through which the amplified energy comes out. The two guides 4 and 5 are coaxial with the cavity 2.

A permanent magnet, or an electromagnet, 6 makes it possible to apply a D. C. magnetic field H_0 to the ferrite rod, parallel therewith. This magnet has the shape of a U and the two side branches of the U are pierced, near their ends, with two circular holes 7 and 8 which have the same diameter as the guides 4 and 5 and which are extensions of the latter. Inside the holes 7 and 8, radial fins are arranged, 9 and 10 respectively, of ferromagnetic material, which, on the one hand, ensure the continuity of the magnetic circuit and, on the other hand, constitute mode filters for the TE_{01} wave to be amplified.

In the cavity, the wave to be amplified is guided by the rod 3 (i. e. the larger portion of its energy is localized in the rod and in the immediate vicinity thereto) in the

2

form of a magnetic field with an ultra high frequency H_a , located inside the rod and directed along its axis, and of an electric field in which the lines of force are circles concentric with the rod and the intensity of which decreases very rapidly when the distance to the rod increases.

5 The cavity 2 is coupled, through a slot 11 with a rectangular guide 12, the axis of which is perpendicular to that of the cavity 2. This guide is energized by a microwave oscillator tube 13 which generates the supply wave with an angular frequency Ω .

10 The cavity 2 is dimensioned so as to resonate with two TM_{11} waves of angular frequency Ω in the vicinity of the cut-off frequency of a circular wave guide having a diameter equal to that of the said cavity. The two TM_{11} waves have magnetic fields (considered at points of the Oz axis of the cavity) of equal magnitudes, but perpendicular to each other and oscillating in phase quadrature. In this manner there is obtained along the said axis a rotating magnetic field and, as the working frequency is in 15 the vicinity of the cut-off frequency of the TM_{11} waves, the magnitude of this magnetic field is the same, whatever be the point of the axis considered.

20 Due to the Faraday effect caused by the magnetized ferrite rod, the resonance frequency of the cavity 2 for the circularly polarized waves depends on the direction of rotation of their electric field. If, for a given direction of rotation of the electric field, the resonance angular frequency of the cavity 2 is equal to Ω , it is sufficient to introduce into the cavity energy with an angular frequency Ω through the slot 11 for this energy to be in 25 the shape of a circularly polarized wave inside the cavity. The magnetic field H_p of this wave rotates with the angular frequency Ω about the axis of the cavity 2.

25 The magnetizing of the ferrite is related to the orientation of the particles, nuclei or electrons, having a magnetic moment M equal to one or to an integral number of Bohr's magnetons, and a kinetic moment J equal to $\frac{1}{2} (h/2\pi)$, h being Planck's constant. The directions of the magnetic and kinetic moments of an electron are 30 identical. Magnetism is caused by unsaturated electron layers in which an electron remains in excess, with its magnetic moment not compensated. Under the action of so-called Weiss forces, all the magnetic moments, not compensated, of the electrons, have a tendency for being 35 oriented parallel to one another. These Weiss forces found an explanation in wave mechanics and are a consequence of Dirac's electron spin theory.

35 The electron which has a very large kinetic moment with respect to the torques applied thereto, reacts like a gyroscope. The energy is supplied to the precession motion by the rotating magnetic field H_p of the waves having an angular frequency Ω . The electromagnetic wave to be amplified, with an angular frequency ω , is amplified at the expense of the nutation motion of the electron. 40 Its magnetic field H_a varying at the angular frequency ω which is that of the nutation motion, the braking of the nutation motion causes, by a gyroscopic effect, a variation of precession and the work of the field H_p against this precession variation sustains the nutation motion.

45 More precisely, it is possible to determine the amplitude of the supply magnetic field H_p and of the D. C. magnetic field H_0 necessary for amplifying a wave having a given angular frequency ω .

50 Reference is made to a tri-rectangular trihedron O , x , y and z . The origin O coincides with an electron located in the ferrite and the axis Oz is directed along the common direction of the axis of the ferrite rod and of the D. C. magnetic field, H_0 .

55 If the electron is moving in any kind of motion, the 55 calculations which follow are not affected since they consider only the motion about the center of gravity.

60 Let $O\xi$ be an axis directed along the straight line of

intersection of the plane going through O perpendicular to the common direction of the magnetic moment M and kinetic moment J, with the plane O, x, y and O η be an axis in the latter plane, at right angle with the axis O ξ .

The field H_p rotating at an angular velocity Ω causes a precession of the direction of the magnetic moment M about O ξ . Since the electromagnetic wave to be amplified can exist in the cavity 2 only in the shape TE₀₁, i. e. has a magnetic field H_a which, along the axis of the cavity 2 is directed along said axis, only the variation of angle θ between the axis O ξ and the direction of the magnetic moment M is corrected with the wave to be amplified, which makes it possible to write (t designating time):

$$\theta = \theta_0 + \theta_1 e^{i\omega t} \quad (1)$$

(designating by θ_1 a complex quantity, the modulus and phase angle of which are shown at the periodically varying part of angle θ).

The variation in nutation causes a variation in precession and one may write, designating by ψ the precession angle (Fig. 2):

$$\psi = \Omega t + \psi_1 \quad (2)$$

and designating by ψ_1 the real portion of $\psi_1 e^{i\omega t}$ (ψ_1 being a complex quantity, the modulus and phase angle of which are those of the periodically varying part of ψ).

The components of the kinetic moment J and of the magnetic moment M are, respectively, in the trihedron O $\xi\eta\zeta$:

$$(3) \quad \begin{cases} J_\xi = 0 \\ J_\eta = -J \sin \theta \\ J_\zeta = J \cos \theta \end{cases}$$

$$(4) \quad \begin{cases} M_\xi = 0 \\ M_\eta = -M \sin \theta \\ M_\zeta = M \cos \theta \end{cases}$$

The components of the derivative of the kinetic moment with respect to time t, for the kinetic moment are in this same trihedron=

$$(5) \quad \begin{cases} \left(\frac{dJ}{dt} \right)_\xi = J \sin \theta \frac{d\theta}{dt} \\ \left(\frac{dJ}{dt} \right)_\eta = -J \cos \theta \frac{d\theta}{dt} \\ \left(\frac{dJ}{dt} \right)_\zeta = -J \sin \theta \frac{d\theta}{dt} \end{cases}$$

The components of the total magnetic field comprising the D. C. magnetic field H₀, the supply magnetic field H_p and the magnetic field of the wave to be amplified H_a are:

$$(6) \quad \begin{cases} H_\xi = H_p \sin \psi_1 \\ H_\eta = H_p \cos \psi_1 \\ H_\zeta = H_0 + H_a \cos \omega t \end{cases}$$

The variations in the direction of the magnetic moment have, as a consequence, an energy radiation.

A portion of this energy is absorbed by the atoms which constitute the crystal lattice of the ferrite in the form of thermal agitation. This energy loss will be neglected in what follows.

The other portion is radiated outside the ferrite and constitutes the available energy. Since, as we saw, only the variation of angle θ is coupled with the radiation, the resulting braking torque is directed along O ξ and the value

$$k J \frac{d\theta}{dt}$$

will be assigned to it, k being a constant and J being placed as a factor, for allowing later simplifications.

In such conditions the resulting torque of the torques exerted can be written:

(7)

$$\begin{cases} C_\xi = M(H_0 + H_a \cos \omega t) \sin \theta + MH_p \cos \psi_1 \cos \theta - k J \frac{d\theta}{dt} \\ C_\eta = -MH_p \sin \psi_1 \cos \theta \\ C_\zeta = -MH_p \sin \psi_1 \sin \theta \end{cases}$$

The derivative of the kinetic moment is equal to the resultant moment for the torques, which gives, identifying the components (5) with the components (7), three equations, two of which are identical.

The following system of equations is thus obtained:

(8)

$$\begin{cases} \frac{d\psi}{dt} = \frac{M}{J}(H_0 + H_a \cos \omega t) + \frac{MH_p}{J} \cos \psi_1 \cotan \theta - \frac{k}{\sin \theta} \frac{d\theta}{dt} \\ \frac{d\theta}{dt} = \frac{MH_p}{J} \sin \psi_1 \end{cases}$$

20

The system of Equations 8 can be transformed, taking the following remarks into account:

The quotient of the moment of a torque by a kinetic moment has the dimensions of a frequency and we may set:

$$\Omega_0 = \frac{M}{J} H_0 \quad (9)$$

$$\Omega_p = \frac{M}{J} H_p \quad (10)$$

Further, H_a cos ωt may be considered as the real portion of H_a $e^{i\omega t}$. The system of Equations 8 then can be written, considering ψ_1' and θ_1 as infinitely small quantities of the first order and neglecting the second order terms:

25 (11)

$$\begin{cases} \Omega + j\omega \psi_1' e^{i\omega t} = \Omega_0 + \frac{MH_a}{J} e^{i\omega t} + \\ \Omega_p \left(\cotan \theta_0 - \frac{\theta_1 e^{i\omega t}}{\sin^2 \theta_0} \right) - \frac{jk \theta_1 e^{i\omega t}}{\sin \theta_0} \\ j\omega \theta_1 e^{i\omega t} = \Omega_p \psi_1' e^{i\omega t} \end{cases}$$

40

Writing the equality of the coefficients of $e^{i\omega t}$ in the second of Equations 11, we obtain:

$$\psi_1' = \frac{j\omega}{\Omega_p} \theta_1 \quad (12)$$

Equating the constant terms in the first Equation 11 we obtain:

$$\cotan \theta_0 = \frac{\Omega - \Omega_0}{\Omega_p} \quad (13)$$

Finally, equating the coefficients of $e^{i\omega t}$ in the first Equation 11 we obtain:

$$\frac{MH_a}{J \theta_1} = \frac{\omega N^2 - \omega^2 + jk\omega\omega_N}{\Omega_p} \quad (14)$$

setting:

$$\omega N^2 = \Omega_p^2 + (\Omega_0 - \Omega)^2 = \frac{\Omega_p^2}{\sin^2 \theta_0} \quad (15)$$

60 ω_N is the natural angular frequency of the nutation motion of the electron. From Equation 14 it may be seen that for a value of ω equal to ω_N , θ_1 may have any value with a zero magnetic field H_a and in the absence of radiation (i. e. $k=0$).

Just as, in traveling wave tubes, the waves which are amplified at the expense of the kinetic energy of the electrons should be propagated with a velocity close to but slightly smaller than that of the electrons, similarly, in the case of the present invention, the amplified wave should have an angular frequency ω close to but slightly smaller than the natural nutation frequency of the electrons, ω_N , so as to continuously brake this nutation.

As a first approximation, we may set:

$$\omega = \omega_N$$

75

In order to have a maximum coupling between the magnetic moment M and the magnetic field H_a , θ_0 should be selected close to 90° , i. e. $\sin \theta_0$ close to unity. There results, then, from Equation 13, that Ω_0 should be close to Ω , which, from Equation 9 gives the value of the D. C. field H_0 (Ω is assumed to be one of the data of the problem). The condition

$$\Omega_0 \approx \Omega \quad (16)$$

is that of the conventional ferromagnetic resonance. In the absence of any magnetic field to be amplified H_a , and of any rotating field H_p , the precession of the electron takes place at a constant angular frequency Ω_0 . This precession motion ceases rapidly when there are losses. In order to sustain it, a rotating field H_p is necessary, with an angular frequency Ω , and the motion is all the better sustained as Ω is closer to the natural angular frequency of precession Ω_0 .

Carrying condition (16) into Equation 15 we derive

$$\Omega_p \approx \omega_N$$

and consequently

$$\Omega_p \approx \omega \quad (17)$$

This latter condition (17) gives, from Equation 10 the value of the rotating field H_p , Ω_p having a very large value of the order, for instance of $100,000 \pi$, Equation 10 also shows that H_p should be very large. As a result, the cavity 2 should have a very large magnification factor for voltage; to this effect, the ferrite rod in which the losses occur should have a very small diameter.

In the above calculations, the losses have been neglected. These losses make it necessary to supply, at the angular frequency Ω a much larger power than that which the circuit makes it possible to obtain on the angular frequency ω .

There will now be obvious to those skilled in the art many modifications and variations utilizing the principles set forth and realizing many or all of the objects and advantages of the invention but which do not depart essentially from the spirit of the invention.

What is claimed is:

1. An amplifier for ultra-high frequency waves and operable in series between two cylindrical wave guides having a common axis and propagating said waves according to the TE_{01} mode, comprising a cylindrical hollow resonator having its axis common with the axis of said guides and coupled to said guides, said resonator including a rod of insulating material of very high magnetic permeability arranged along its axis, means for impressing upon said rod a direct-current magnetic field parallel to said axis and means for exciting in said resonator an auxiliary circularly polarised TM_{11} wave, the frequency of which is lower than the frequency of said waves to be amplified, said insulating material being a ferromagnetic material characterized by a resonance frequency and said resonator being tuned to the frequency of said auxiliary wave, the latter frequency substantially coinciding with the ferromagnetic resonance frequency of said material for a predetermined rotational direction of said circularly polarized waves.
2. An amplifier as claimed in claim 1, wherein said material is a ferromagnetic ferrite.
3. An amplifier as claimed in claim 1, wherein said auxiliary wave is applied to said resonator by means of an auxiliary guide coupled to said resonator.
4. An amplifier as claimed in claim 1, wherein the frequency of said auxiliary wave is about one-tenth of the frequency of the waves to be amplified.
